UNITED STATES PATENT OFFICE

2,455,952

MAGNETRON

Robert C. Schmidt, Newton, Mass., assignor to
 Raytheon Manufacturing Company, Newton,
 Mass., a corporation of Delaware

Application January 9, 1945, Serial No. 572,035

4 Claims. (Cl. 250—27.5)

1

This invention relates to electron discharge devices such as magnetrons, for example, and more particularly to those of small dimensions and relatively low power.

One object of the present invention is to provide a device of the aforesaid general type which can be produced at relatively low cost and which can be used to advantage in radar transmitter circuits or as a local oscillator in radar receiving circuits and under other situations where space and weight may be determining factors.

Another object of the present invention is to provide an electron discharge device of the general type referred to having a compact structure and arrangement of the parts and which is self-contained.

These and such other aims and objects of the invention as may hereinafter appear will be best understood from the following description, taken in connection with the accompanying drawing of one embodiment of the invention.

In the drawing:

Fig. 1 is a vertical section on line 1—1 of Fig. 2 of an electron discharge device incorporating one illustrative embodiment of the invention;

Fig. 2 is a horizontal section on line 2—2 of Fig. 1;

Fig. 3 is a vertical section on line 3—3 of Fig. 2; and

Fig. 4 is a horizontal section on line 4—4 of Fig. 1.

The illustrative embodiment of the invention shown in the drawing comprises an anode structure consisting of a cylinder 2 having a central wall 4 projecting from its inner surface, said wall being provided with a central circular aperture 6 to the walls of which are soldered a plurality of radially disposed, suitably spaced, plates or arms 8. Said cylinder 2 and its integral wall 4 will preferably be made of copper and said plates 8 may be conveniently stamped out of a sheet of highly conductive copper. The inner ends of said plates or arms 8 form anode faces 10 which constitute electron receiving portions and cooperate with a cathode 11 having its active portion 12 supported substantially centrally of and coextensive with said anode faces. Pole pieces 14 and 16 are provided at opposite sides of said aperture 6 and concentrically with the latter and extend into the open ends of said cylinder 2 and into proximity with said anode arms. Said anode structure is supported by electrically conductive rods 18 which are sealed through porcelain seals 20 (only two of which are shown) in said wall 4, the ends being soldered in flanges

2

22 and 24 of said pole pieces 14 and 16, respectively. Headers 26 and 28 of steel or other suitable magnetic metal are soldered to the two ends, respectively, of a cylinder 30 of electrically conductive non-magnetic metal, such as copper, and which possess a relatively high coefficient of thermal conductivity. Said headers thus form with said cylinder 30 an envelope containing all the parts so far described and which can be evacuated through a pipe 32 which is then sealed.

Leaving the ends of the anode cylinder 2 open and enclosing the cathode structure in the larger envelope constituted by the copper cylinder 30 and the two headers 26 and 28 provide increased radiation surface to cool the anode. It will also be noted that the above described arrangements of the different parts provide a very compact and light device requiring relatively little space.

The flange 24 of pole piece 16 is spot-welded to said header 28, the other header 26 being slightly spaced from the pole piece 14.

The cathode 11 will preferably be of the indirectly heated thermionic type comprising a hollow cylinder of electrically conductive material, nickel for example, containing a heater wire 34. The active portion 12 of said cathode can be coated with an electron emissive substance, such as oxides of the alkaline earth metals. Said cathode fits tightly in an electrically non-conductive nipple 36 inserted in the lower end of a bore 38 extending centrally through said pole piece 16 and in alignment with a similar bore 40 in the pole piece 14, and the upper end of the cathode is received in said bore 40 which is of less diameter than said bore 38 in order to fit the cathode which is thus securely centered and electrically connected to said pole piece 14, said cathode being provided with a small longitudinal rib 41 which fits in a slot 43 in the wall of said bore 40. Said pole piece 14 may be copper plated to increase its conductivity. The heater wire 34 extends axially of the cathode, its upper end being connected to the inner surface of the cathode and its other end to a conductor 44 connected in turn to a lead-in conductor 46. From said pole piece 14 the heater wire circuit continues through the rods 18 and the header 26 to the lead-in conductor 47. The anode lead-in conductor is shown at 49 sealed through said header 28 (see Fig. 3).

A cylindrical magnet 48 for exciting the pole pieces 14 and 16 may be fitted around the copper cylinder 30 and may thus form a part of the structure forming the object of the present in-

vention. The result is a complete self-contained compact device.

If the above described electron discharge device be energized and the pole pieces 14 and 16 excited by said magnet, oscillations will be generated in said device which may be led out through a suitable coaxial line by means of a coupling loop 50 extending into the anode structure above the space of a resonator cavity between two of said anode arms 8. One end of said coupling loop 50 is connected to the inner end of a tubular structure comprising pipes 52 and 58, and the other end of said loop 50 is connected to a conductor 54 which extends axially of said two pipes 52 and 58 and is sealed through a porcelain seal 56 carried by said header 28, said conductor 54 thus forming with said pipes 52 and 58 a coaxial line through which the high frequency oscillations generated by the device may be conducted to any suitable utilization circuit. To keep said conductor 54 centered in the pipe 58, insulating material 57 may be provided in said pipe between said conductor and the walls of said pipe.

Each pair of anode arms 8 forms with the portion of the wall 4 between them an oscillating cavity or cavity resonator. A capacitance exists between the cathode and the end faces of said anode arms and also between the side walls of each cavity resonator. The conductive path around each cavity resonator afforded by the walls thereof constitutes an inductance. The anode therefore is so designed and spaced relatively to the cathode that said inductances and capacitances constitute tuned circuits.

Electron discharge devices embodying the present invention are especially useful in laboratory work for the measurement of frequency wherever ultra-short waves are concerned, more particularly micro or centimeter waves. The device is very compact, thus requiring little space, and can be produced at relatively low cost.

I am aware that the present invention can be embodied in other specific forms without departing from the spirit or essential attributes thereof, and I therefore desire the present description to be considered in all respects as illustrative and not restrictive, reference being had to the appended claims rather than to the aforesaid description to indicate the scope of the invention.

What is claimed is:

1. An electron-discharge device comprising: a cathode; an anode structure, including a plurality of cavity resonators, spaced from and surround-

ing said cathode; opposed pole pieces at opposite ends of said cavity resonators; an hermetically sealed envelope enclosing said cathode, said anode structure, and said pole pieces; and means, carried by said pole pieces independently of and spaced from said envelope, supporting said anode structure.

2. An electron-discharge device comprising: a cathode; an anode structure, including a plurality of cavity resonators, spaced from and surrounding said cathode; opposed pole pieces at opposite ends of said cavity resonators; an hermetically sealed envelope enclosing said cathode, said anode structure, and said pole pieces; means, carried by said pole pieces independently of and spaced from said envelope, supporting said anode structure; and a cylindrical magnet surrounding said envelope.

3. An electron-discharge device comprising: a cathode; an anode structure, including a plurality of cavity resonators, spaced from and surrounding said cathode; opposed pole pieces disposed at opposite ends of said cavity resonators; a supporting member extending between said pole pieces and passing through said anode structure; and means, carried by said anode structure, insulatedly supporting said anode structure from said supporting member.

4. An electron-discharge device comprising: a cathode; an anode structure, including a plurality of cavity resonators, spaced from and surrounding said cathode; opposed pole pieces disposed at opposite ends of said cavity resonators; an electrically-conductive rod extending between said pole pieces and passing through said anode structure; and an insulator, carried by said anode structure and engaging said rod, and supporting said anode structure from said rod.

ROBERT C. SCHMIDT.
